United States Patent Office.

WILLIAM A. DEMUTH, OF NEW YORK, N. Y.

Design No. 4,856, dated May 2, 1871.

DESIGN FOR BOTTLE.

The Schedule referred to in these Letters Patent and making part of the same.

To all whom it may concern:

Be it known that I, WILLIAM A. DEMUTH, of New York city, in the county and State of New York, have invented a new and original Design for a Bottle; and I do hereby declare that the following is a full, clear, and exact description thereof, which will enable others skilled in the art to make and use the same, reference being had to the accompanying drawing forming part of this specification.

The drawing represents a side view of my new design for a bottle.

This invention relates to a new form of bottle, and consists in making the same in form of a mouse with the opening at the snout, as shown.

I claim as my invention—

The design for a bottle, as shown.

WM. A. DEMUTH.
